UNITED STATES PATENT OFFICE.

WILLIAM MAINLAND BROWN, JR., OF SACRAMENTO, CALIFORNIA.

APPARATUS FOR OPERATING SAFETY-GATES OF RAILWAY-CARS.

SPECIFICATION forming part of Letters Patent No. 403,176, dated May 14, 1889.

Application filed March 21, 1888. Serial No. 267,953. (No model.)

To all whom it may concern:

Be it known that I, WILLIAM MAINLAND BROWN, Jr., of Sacramento, in the county of Sacramento and State of California, have invented new and useful Improvements in Apparatus for Operating the Safety-Gates of Railway Passenger-Cars, of which the following is a full, clear, and exact description.

This invention relates to an apparatus by means of which gates inclosing the platforms of railway-cars are operated by the engineer of the train.

The invention has for its object to prevent passengers from falling off the platforms of railway-cars, and to provide an operating mechanism for opening and closing gates located at the sides of the platforms of railway passenger-cars, and which are controlled and operated from the engine of the train.

The invention consists in mechanism for operating safety-gates inclosing the platforms of railway passenger-cars connected with the engine or locomotive of the train, all constructed and arranged as hereinafter described and claimed.

Reference is to be had to the accompanying drawings, forming a part of this specification, in which similar figures of reference indicate corresponding parts in all the views.

Figure 1 is a side view of the end of a passenger-car, showing a safety-gate in open position, with connecting mechanism partly broken away. Fig. 2 is a similar view showing a gate closed. Fig. 3 is an end view of a passenger-car with platform in section, showing the gates and their pockets or casings. Fig. 4 is a detail plan view, in horizontal section, of a corner of a car, showing a gate closed. Fig. 5 is a similar view showing a gate open.

Fig. 6 is a detail view of one of the brackets for supporting the operating mechanism. Fig. 7 is a detail view, with parts broken away and in section, of one of the safety-gates. Fig. 8 is a detail view, partly in section and broken away, of a car-floor, showing one of the supporting-rollers. Fig. 9 is a detail view showing double supporting-rollers at the top of a gate. Fig. 10 is a detail view showing a portion of a gate with supporting-roller. Fig. 11 is a view looking at the under side of a passenger-car, showing the position of the operating mechanism when the gates are closed. Fig. 12 is a similar view showing the position of the operating mechanism when the gates

are open. Fig. 13 is a detail view representing a portion of the mechanism at the center of the car for operating the gates. Fig. 14 is a detail view showing the steam-cylinder, the piston, and a portion of the steam-supply pipes, with parts broken away, which connect with the safety-gates. Fig. 15 is a detail view of one of the brackets supporting the piston which operates the safety-gates. Fig. 16 is a detail plan view, with parts broken away, showing a portion of the operating-levers connected with the safety-gates. Fig. 17 is a side view thereof. Figs. 18 and 19 are detail views showing the brackets supporting the operating mechanism of the safety-gates. Fig. 20 is a detail view, with parts broken away and in section, of a portion of the safety-gate-operating mechanism.

In carrying out this invention the platforms of a passenger-car are provided with gates 1, of suitable open-work material, which are located so as to cover the space between the last step of the platform and the sides and stanchions 2 of the car. The gate is mounted by means of rollers 3 on tracks 4. The upper tracks, 4, extend from the stanchion 2 into a pocket, 6, in the side of the car, and the lower track, 5, extends from one of the supports 7 of the steps, and is bent up with its end secured to the bottom of the car. The lower track, 5, is formed with a projection, 8, adjacent to its forward end, and projections 9 adjacent to its rear end, whereby, when the gate is closed, the forward roller 3 will be prevented by the projection 8 from being moved back, and the rear roller 3 will be locked between the projections 9 and hold the gate from moving forward when in open position.

A gate constructed and arranged similarly to 1 is located on each side of the platform.

To operate the gates, each gate 1 is connected by means of a pivoted rod, 10, with levers 11, pivoted in brackets 12 on the under side of the car, and extending through the guide-brackets 13. The inner ends of the levers 11 are provided with slotted ends 14, with which the pin 15 on a rod, 16, engages. The rod 16 extends through a guide bracket or hanger, 17, on the bottom of the car and pivotally connects with a double-ended lever, 18, mounted at about the center of the car in suitable hangers, 19. At one end of the double-ended lever 18 is pivoted a crank-arm,

20, having its other end pivoted to a block, 21, sliding in a frame, 22, supported at one end by a bracket, 23, on the bottom of the car, and at its other end connected to a cylinder, 24, 5 mounted in brackets 25, depending from the bottom of the car. The sliding block 21 has secured to it a piston-rod, 26, having a piston-head, 27, located in the cylinder 24. The end of the cylinder 24 behind the piston 27 connects by means of a branch pipe, 28, with a main supply-pipe, 29, leading to the locomotive of the train. The end of the cylinder 24 in front of the piston 27 connects by means of a branch pipe, 30, with the main 15 supply-pipe 31, leading to the locomotive.

It will be understood from the foregoing description that each end of a car is provided with sliding gates 1, constructed and arranged similarly to the gates 1 already described, and 20 connected by similar operating mechanism with the ends of the double-ended lever 18, so that the movement of the latter will act to open or close the gates.

In order to suitably connect the main supply-pipes 29 and 30 between the cars of a train, they are provided with a suitable coupling. (Not shown in the drawings.)

When the gates are open, as shown in Fig. 1, the operating mechanism beneath the car 30 will be located in the position shown in Fig. 12. To close the gates, the engineer permits steam to enter the main supply-pipe 29, which thereby acts upon the piston-head 27 and forces it forward, pulling on the rods 16 and 35 closing the gates 1. To open the gates, steam is supplied to the pipe 31, and, acting upon the piston-head 27, forces it back, thereby pushing the rod 16, and by means of their connections drawing back the gates 1.

40 It will be seen by the location of the gates that they may be conveniently slid back out of the way, and the handle 44 on the car, being located inside of the gates, cannot be reached when the gates are closed. Furthermore, in 45 case of sudden swaying of the cars, passengers crossing from one car to another or standing upon the platform will be prevented by the gates from being thrown off of the train.

While I have described a particular construction of parts, I do not desire to limit myself thereto, as they may be varied in form and arrangement without departing from the essential features of the invention.

If desired, compressed air may be employed 55 instead of steam to operate the gates. The gates are easily operated, and will be simultaneously opened or closed, at the will of the engineer.

Having thus described my invention, I claim 60 as new and desire to secure by Letters Patent—

1. The combination, with the car, the four gates at the steps thereof, of the horizontal lever 18, pivoted between its ends to the under 65 side of the car, oppositely-projecting rods 16, pivotally connected at their inner ends with the ends of said lever, two transverse levers,

11 11, pivoted at each end of the car, with their inner ends, 14, overlapped and slotted, a pin or bolt extending through said slots into the outer ends of the two rods 16, a rod connecting the end of each lever 11 with a gate, and means for operating the lever 18 to throw and retract the rods 16, substantially as set forth. 70

2. In an apparatus for opening and closing 75 the safety-gates of a passenger-car, the combination, with the cylinder 24, connected by means of main supply-pipes 28 and 30 with pipes 29 31, and having the piston-head 27 with piston-rod 26, and sliding block 21, 80 mounted on frame 22, of the double-ended lever 18, mounted in brackets 19, connected at one end by means of pivoted rod 20 with sliding block 21, actuating-rod 16, connected at one end with the double-ended lever 18, 85 mounted in brackets 17, and having a pin, 15, levers 11, pivoted in brackets 12, having slotted ends 14, engaging pin 15, and the bars or rods 10, connecting levers 11 with gates 1, all located and arranged beneath a car, substantially 90 as described.

3. In an apparatus for opening and closing 95 the safety-gates of a railway passenger-car, the combination, with sliding gates 1, having grooved rollers 3, mounted on tracks 4 5, the 100 tracks 5, having projections 8 and 9 9 located at the forward and rear ends thereof, the pockets or recesses 6, to receive the gates, pivoted rods 10, connected with said gates and with pivoted levers 11, and actuating-rods 16, having a pin, 15, at one end, engaging the slotted ends 14 of levers 11, and pivoted at their other ends to a double-ended lever, 18, in combination with rod 20, pivoted to one end of double lever 18 and at its other end to block 21, sliding 105 in frame 22, piston 27, connected with block 21, cylinder 24, branch pipes 28 and 30, and main supply-pipes 29 and 31, leading to the locomotive, substantially as shown and described. 110

4. An apparatus for operating the safety-gates of railway passenger-cars, consisting of sliding gates 1, having rollers 3, mounted on tracks 4 5, the latter having stops 8 9 9, levers 11, pivoted rods 10, connecting with gates 1, 115 double-ended lever 18, with actuating-rods 16, having a sliding connection with the slotted ends of levers 11, cylinder 24, with piston 27, connecting with double lever 18, main steam-supply pipes 29 31, connecting with the ends 120 of cylinder 24 by branch pipes 28 and 30, and couplings connecting the sections of pipes 29 and 31, consisting of sections 32 clamped thereto, and having automatically-closing 125 hooks 33, lugs 35, guide projections 37, and lugs 38, automatically-closing valves 40, and projecting arms 43, holding valves 40 open, all constructed and arranged substantially as shown and described.
